AUXILIARY FEEDING MEANS FOR
HOSIERY SEAMERSJohn A. Pons, Morganton, N. C., assignor to The
Singer Manufacturing Company, Elizabeth,
N. J., a corporation of New Jersey

Application April 6, 1948, Serial No. 19,193

20 Claims. (Cl. 112—18)

1

This invention relates to improvements in hosiery seaming machinery and more especially to a machine for seaming ladies hosiery at high speed.

Heretofore, the hosiery to be seamed has been fed through the seaming machine by means of a pair of driven contra-rotation feeding cups disposed adjacent each other, on a horizontal plane, and these feeding cups have fine teeth cut in their outer peripheries which are adapted to mesh when there is no hosiery blank in the machine. One of the feeding cups is mounted on a stationary vertical axis and the other of the feeding cups is mounted on a resilient vertical axis so that when a blank is fed between the feeding cups the teeth on the periphery of the feeding cups engage opposite sides of the blank immediately below the selvedge edges thereof.

The resiliency of one of the feeding cups is adjustable to thereby increase or decrease the pressure exerted on the blank as it is passed between the proximate edges of the feeding cups in a seaming operation. Now, as the feeding cups feed the blank through the seaming machine the pressure of the cut teeth on the peripheries of the two feeding cups often severs one or more of the threads in the blank immediately below the seam and thus cause runs and pull threads in the hose.

It is therefore an object of this invention to provide means cooperating with the feeding cups to thereby assist in drawing the hosiery blank through the machine so that the pressure existing between the feeding cups may be adjusted to decrease this pressure so as not to injure the hose.

It is another object of this invention to provide means for holding the hose taut after the hose has been seamed in the conventional manner to thereby insure a more consistent uniformity in the stitches of the seam for the entire length of the hose than has heretofore been possible.

It is another object of this invention to provide a pair of lightly knurled driven contra-rotating, and resiliently mounted rollers disposed in the path of the hose as it is fed through the machine and between which the seamed portion of said hose passes, said seam being engaged by the rollers to not only assist in moving the hose through the machine but the pressure of these rollers being exerted on opposed sides of the seam instead of that portion of the hose immediately below the seam thus eliminates the main cause of hosiery being damaged in the seaming operation.

When the hose is made of very soft and pliable thread, such as 10, 15 and 20 denier, the conventional feeding cups have heretofore, in many instances, caused the selvedge edges of the hose to bunch up between the feeding cups as they are fed to the same by an operator and the feeding cups would not carry the selvedge edges through

2

the machine properly. This not only causes a number of stitches to be repeated through one point of the stitched edges, but also causes the material which is bunched up between the feeding cups to be torn and thus completely ruin the hose. It is therefore another object of this invention to overcome this condition by having the knurled rollers disposed in the path of the stitched edge of the hose and these knurled rollers resiliently engage each side of the seam of the hose at the level of the needle and thus draw the hose through the machine and thus take this responsibility away from the feeding cups.

Some of the objects of the invention having been stated, others will appear as the description proceeds when taken in connection with the accompanying drawings in which:

Figure 1 is a front elevation of a conventional "Singer" seaming machine with parts broken away and showing the invention associated therewith;

Figure 2 is a side elevation of the upper front portion on an enlarged scale, looking from the left-hand side of Figure 1 to the right and is taken substantially along the line 2—2 in Figure 1 but shows some of the parts in a different position;

Figure 3 is a sectional plan view of the front portion of the machine and is taken substantially along the line 3—3 in Figure 2 with cover 181 removed;

Figure 4 is a vertical sectional view of the invention taken substantially along the line 4—4 in Figure 3;

Figure 5 is a sectional plan view taken substantially along the line 5—5 in Figure 1 showing the leg portion of the hose being fed through the machine;

Figure 6 is a sectional plan view similar to Figure 5 but showing the welt portion of the hose being fed through the machine;

Figure 7 is a vertical sectional view taken substantially along the line 7—7 in Figure 3 with the lower portion of the invention broken away;

Figure 8 is a plan view of the central left-hand portion of Figure 3 but showing the cover for the pinions in place and showing other parts in a different position;

Figure 9 is an enlarged elevation of the front portion of the machine with parts broken away and being taken substantially along the line 9—9 in Figure 1;

Figure 10 is a sectional plan view taken along the line 10—10 in Figure 9;

Figure 11 is an isometric view of the invention removed from the machine and omitting the gear cover from the same;

Figure 12 is a view looking up substantially along the line 12—12 in Figure 11 with parts broken away;

Figure 13 is a plan view similar to Figure 5 showing the movable parts schematically and in a different position;

Figure 14 is a schematic elevation of the parts shown in Figure 13 and is taken substantially along the line 14—14 in Figure 13;

Figure 15 is a plan view similar to Figure 13 but showing the movable parts in another position;

Figure 16 is a schematic elevation similar to Figure 14 but showing the parts in another position and being taken substantially along the line 16—16 in Figure 15;

Figure 17 is a plan view similar to Figure 13 but showing the parts in still another position;

Figure 18 is an elevation similar to Figure 14 showing the parts in still another position and being taken substantially along the line 18—18 in Figure 17.

Referring more specifically to the drawings the numeral 10 indicates a conventional cast housing of the seaming machine which has confined therein conventional means for driving the various parts of the machine to be hereinafter described. This housing 10 has, rotatably mounted therein and projecting therefrom, a horizontally disposed shaft 11 on which is fixedly mounted a grooved pulley 12. This pulley 12 has mounted thereon the upper end of a belt 13 which extends downwardly to a suitable driving means, not shown.

The lower portion of the housing 10 projects towards the observer in Figure 1 and has integral therewith a boss 15 which also has integral therewith an upwardly extending sleeve 16 which is integral at its upper end with an outwardly projecting portion 17 which is integral with, and extends outwardly from, the front vertical surface of the housing 10.

Rotatably mounted in the boss 15, the sleeve 16, and the outwardly projecting portion 17, is a vertically disposed shaft 18 which is driven at its lower end by conventional means confined within the housing 10. The vertically disposed shaft 18 extends upwardly above the outwardly projecting portion 17 and has, fixedly mounted thereon, by any suitable means such as set screws 23 (Figures 9 and 10), a conventional rear circular feeding cup 20 which has serrations or teeth 21 cut in its outside periphery and has a hub portion 19 integral therewith and extending downwardly therefrom (Figure 9).

Disposed within the feeding cup 20, and extending above the upper edge of the same, is a conventional fabric guide 24 which is secured, by any suitable means such as screws 25, to an L-shaped bracket 26 which is secured, by screws 27, to a boss 30 integral with the front vertical surface of the housing 10 (Figures 3 and 9). The fabric guide 24 has secured thereon, by screws 31, a conventional chaining finger 32 which projects forwardly and to the left, in Figure 3, and has a tapering pointed portion 33 integral therewith.

The fabric guide 24 has a transverse groove 35 therein (Figure 3) which is penetrated by a conventional gauge needle 36. The gauge needle 36 is securely mounted in a conventional needle clamp 37, by a set screw 38. The needle clamp 37 is secured to the front end of a conventional needle bar 40, by a screw 41. This needle bar 40 has reciprocating forward and rearward movement in the housing 10 and is driven by conventional means, not shown, disposed within the housing 10.

The forward end of the needle bar 40 has, inte-

gral therewith, an outwardly projecting portion 42 in which a vertically disposed stub shaft 43 is fixedly mounted. The stub shaft 43 extends upwardly and has, oscillatably mounted thereon, a conventional arm 45 (Figures 1 and 2) which has a conventional socket portion 46 secured on its free end, by screws 47, and this socket portion 46 has, oscillatably mounted therein, a ball portion 49 (Figure 1) disposed on the lower end of an arm 48 which is fixedly secured at its upper end to one end of a shaft 50, by a screw 51. The screw 51 also secures an upwardly projecting wire thread guide 52 to the end of the shaft 50.

The shaft 50 is oscillatably mounted in a bearing portion 53 of a downwardly projecting bracket 54 which is secured at its upper end to the lower surface of a forwardly projecting portion 55 of the conventional housing 10, by conventional means, not shown. The front end of the shaft 50 has clamped thereon, a screw 57, a downwardly projecting arm 60, which has secured thereto, by a screw 61, a conventional left-hand looper 63 which extends towards the chain finger 32 in Figure 3. The left-hand looper 63 has secured to the front vertical surface thereof, by screws 64, a conventional needle guide 65 which also extends downwardly and towards the chaining finger 32, but the free end of the same diverges in spaced relation to the free end of the conventional left-hand looper 63.

Projecting downwardly from within the outwardly projecting portion 55 of the housing 10, is a split collar 65' which has outwardly extending ears 66 integral therewith, one of which is slidably penetrated by a screw 67 and this screw 67 is threadably imbedded in the remaining ear 66 to thus clamp the collar 65' around a downwardly projecting sleeve 70. This collar 65' is an integral part of a conventional springs means within the housing 10, not shown, for urging the collar 65' and associated parts inwardly, or to the left, as observed in Figure 2 and to thus urge a front feeding cup 72, to be presently described, inwardly towards the rear feeding cup 20.

The sleeve 70 is penetrated by a vertical disposed shaft 71 (Figure 3) which is rotatably mounted within the sleeve 70 and is driven at its upper end by conventional means, not shown, confined within the housing 10. The lower end of the vertically disposed shaft 71 has integral therewith the conventional front circular feeding cup 72. This front circular feeding cup 72 has serrations or teeth 73 cut in its outside periphery which are adapted to engage the teeth 21 of the rear feeding cup 20, when there is no hose in the machine, and are urged against the same by conventional means, not shown, confined within the outwardly projecting portion 55 of the seamer housing 10.

Integral with the lower end of the sleeve 70 is a disk 75 which is disposed within the front feeding cup 72. This disk 75 has mounted thereon, by screws 76, a conventional needle guide 77 (Figures 3, 5, 6 and 13 to 18). The needle guide 77 has a groove 78 extending longitudinally thereof, that is, from the junction point of the two feeding cups 24 and 72, to the vertically disposed sleeve 70 (Figure 3). This groove 78 is also in alignment with the groove 35 in the fabric guide 24.

There is also projecting downwardly, from within the outwardly projecting portion 55 of the seamer housing 10, a bearing member 85 (Figure 1). This bearing member 85 has conventional levers 86 and 87 extending outwardly therefrom

which are adapted to be engaged by one's fingers, on opposed side thereof, and urged towards one another at their outer ends and, inasmuch as they pass each other intermediate their ends they are moved away from each other at their inner ends. These levers 86 and 87 are pivotally mounted in a conventional manner and are urged towards each other, near their left-hand ends in Figure 1, by a tension spring 88 which is secured at each end to the levers 86 and 87 respectively. The levers 86 and 87 are employed as part of a locking device in association with a conventional uncurler unit, broadly designated at 91, and extending downwardly therefrom. This uncurler unit 91 is swingably mounted on the downwardly projecting bearing portion 85 and comprises a center uncurler plate 93 which has, disposed on each side thereof, outside uncurler plates 92 and 94 (Figures 1 and 5) which are spring pressed by conventional means, not shown, towards the center uncurler plate 93. The outside uncurler plates 92 and 94 are pivotally mounted adjacent their upper ends, on a stub shaft 95 (Figure 1), and these uncurler plates 92 and 94 extend upwardly above the uncurler plate 93 and have concavo-convex portions 96 integral therewith which are adapted to be urged apart from each other by a compression spring, not shown, disposed between the concavo-convex portions 96. The stub shaft 95 is fixedly mounted in a portion 97 of the uncurler unit 91 which projects downwardly from the bearing portion 85.

The seamer housing 10 has projecting outwardly therefrom a conventional boss 108 (Figure 1) having a shaft 101 oscillatably mounted therein. This shaft 101 is driven by conventional means disposed within the housing 10. The shaft 101 has fixedly mounted on the inner end of the same a conventional right-hand looper 102. The boss 108 is cut away as at 103 and the shaft 101 has, integral therewith and projecting upwardly through the cut-away portion 103, a conventional three-thread take-up arm 104.

The seamer housing 10 also has projecting outwardly therefrom, conventional tension assembly units broadly designated at 105, 106, and 107. The tension assembly units 106 and 107, being identical, like reference characters will apply to the tension assembly unit 107 as those applying to the tension assembly unit 106, with the prime notation added. The tension assembly unit 106 comprises a shaft 109 which is integral with and projects outwardly from the left-hand side of the housing 10 in Figure 2 and has secured thereto a bracket 110 having outwardly projecting ears 111 and 112 which are perforated as at 114 and 115, respectively. This shaft 109 has integral therewith a conventional tension disk 117 which is engaged by another conventional tension disk 118 which is urged against the tension disk 117 by a compression spring 120 which engages, at its outer end, a knurled adjustment nut 121 which is threadably mounted on the outer end of the shaft 109.

The tension assembly unit 105 is very similar to the tension assembly units 106 and 107 with the exception that it has a bracket 125 having a vertically disposed portion 126 integral therewith which is adapted to guide a thread 127 through the tension assembly unit 105 the right-hand side of the housing 10 in Figure 1. The bracket 125 also has, disposed at its lower end, an outwardly projecting ear 130 having a hole 131 therethrough through which the thread 127 passes to the needle in a manner to be later de-

scribed. The tension assembly unit 105 also comprises a shaft 135 which has integral therewith a disk 136 which has urged against the same a tension disk 137, by a compression spring 139 the other end of which engages a knurled adjustment nut 138 which is threadably mounted on the outer end of the shaft 135.

Extending from suitable spools of a conventional thread unwinder, not shown, are threads 10 127, 140 and 141. The thread 127 passes between the tension disks 136 and 137 (Figure 1) and then passes downwardly through the hole 131 in the outwardly projecting portion 130. The thread 127 passes downwardly through the upwardly projecting thread take-up arm 104 and then downwardly through the lower portion of the needle clamp 37 and then forwardly and upwardly through the eye of the gauge needle 36 and finally through the edges 147 and 148 of a hose 150.

The thread 140 passes through one or more of the perforations 114 in the bracket 110, then between the tension disks 117 and 118 and then through the hole 115 in the outwardly projecting portion 112 of the bracket 110. The thread 140 then passes downwardly through a hole 139 in the bracket 54, downwardly through the heel of the left-hand looper 63 and outwardly through the eye in the free end of the looper 63 and finally to the selvage edges 147 and 148 of the hose 150.

The thread 141 passes through one or more of the holes 114' in the bracket 110' and then passes between the tension disks 117' and 118' and outwardly through the hole 115' in the outwardly projecting portion 112' of the bracket 110'. The thread 141 then passes downwardly through the hole 142 in the downwardly projecting bracket 54 and thence downwardly through the heel of the conventional right-hand looper 102 and then downwardly through an eye in the lowermost end of the right-hand looper 102. Thus the seaming machine is threaded for a conventional three-thread stitch.

45 The two edges 147 and 148 of the hose 150, that are to be seamed, pass on each side of the center uncurler plate 93 and edge 147 passes between the center uncurler plate 93 and the inside uncurler plate 92. The edge 148 passes between center plate 93 and front plate 94. The rear feeding cup 20 rotates in a clockwise direction in Figure 3 and the front feeding cup 72 rotates in a counter-clockwise direction in Figure 3 to thus move the edges 147 and 148 of the hose 150, which is engaged by the proximate edges of the feeding cups 20 and 72, from right to left in Figure 3. The uncurler plates 92, 93 and 94 are conventional means for uncurling the selvage edges 147 and 148 of the hose blank 150 as they are fed to the feeding cups 20 and 72.

65 As the selvage edges 147 and 148 of the hose 150 pass between the feeding cups 20 and 72 the gauge needle 36 moves from its rearmost position, substantially as shown in Figure 15, through the uppermost edges 147 and 148 of the hose 150 and to the position shown in Figure 3.

70 As the gauge needle 36 moves forwardly the left-hand looper 63 and the needle guide 65, which is integral therewith, move downwardly and to the left from the position shown in Figures 15 and 16 to the position shown in Figures 3, 5 and 6. Also, at this same time, the right-hand looper 102 moves downwardly and then upwardly from the position shown in Figure 14

to the position shown in Figure 18 and then to the position shown in Figure 16.

The gauge needle 36 then moves rearwardly out of the hose 150 and at the same time the left-hand looper 63 passes under a loop, formed against the tapered portion 33 of the chaining finger 32 as the gauge needle moves rearwardly and moves the same upwardly as the left-hand looper 63 moves upwardly and then the right-hand looper moves downwardly from the position shown in Figure 14 to the position shown in Figure 18. The reciprocatory motion of the needle 36, the left-hand looper 63 and the right-hand looper 102 is caused by conventional parts within the housing 10 and this reciprocatory motion forms chain stitches 152 over the pointed portion 33 of the chaining finger 32 and these stitches 152 slide off of the portion 33 as the hose 150 continues through the machine and thus form the seam on the hose 150.

All of the parts heretofore described are conventional parts of a hosiery seamer such as is manufactured by the Singer Manufacturing Company under their number 242-1, a more complete description of which may be found in their instruction booklet form 19537 revised (142), and bearing copyright 1940 and 1942, and it is in association with these parts that this invention is adapted to be used.

Now, as heretofore stated, uniformity of the stitches 152 is more efficiently produced by the hose being held taut at an unchanging amount of tension from the time the hose starts to pass from between the feeding cups 20 and 72 until the hose is completely seamed. This is insured by a pair of knurled rollers 160 and 161 between which the seam of the hose 150 passes after it leaves the feeding cups 20 and 72. The knurled roller 161 is rotatably mounted on a fixed axis, while the roller 160 is rotatably mounted on a spring-pressed axis, in a manner to be presently described. The improved, new structure comprises a gear wheel 163 which is fixedly mounted on the hub portion 19 of the rear feeding cup 20, by any suitable means such as set screws 164. It may be observed in Figures 9 and 10 that the hub 162 of the gear wheel 163 has bores 165 therein to permit access to the set screws 23 which secure the feeding cup 20 on the shaft 18. There is disposed around the gear wheel 163 a curved guard plate 166 which is turned outwardly, as at 167, and is secured to the front face of the bracket 26 by the lowermost of the screws 27 (Figure 9). This guard plate 166 passes from the front face of the bracket 26 forwardly around the gear wheel 163, the curvature of the same conforming substantially to the periphery of the feeding cup 20. The free end of the guard plate 166 then extends from the front edge of the feeding cup 20, to the left in Figure 5, parallel to the path of the hose 150, to where the free end of the guard plate 166 is adjacent a pinion 170.

The pinion 170 is engaged and driven by the gear wheel 163 and this pinion 170 is fixedly mounted on the restricted lower end of a vertically disposed shaft 171, and is secured on the same, by any suitable means such as a dowel pin 172 (Figure 12). The shaft 171 is rotatably mounted in an upwardly projecting portion 173 of a substantially Z-shaped bracket, broadly designated at 175.

This bracket 175 comprises a horizontally disposed portion 176, a downwardly projecting rear portion 177, the upwardly projecting front portion 178 and a horizontally disposed plate portion

180 all of which are integral and the horizontally disposed plate portion 180 projects forwardly of the upwardly projecting portion 173. The downwardly projecting rear portion 177 has a bore 182 therethrough which is penetrated by a screw 183 (Figure 1), the other end of which is threadably embedded in the conventional seamer housing 10, to thus secure the bracket 175 to the housing 10. The upwardly projecting portion 173 of the bracket 175 is cut away as at 184 on somewhat of an angle so that the bracket 175 will not engage that portion of the rear feeding cup 20 which is adjacent the bracket 175.

The horizontally disposed plate portion 180 has recesses 187, 190, 191, 192 and 193 which are adapted to receive pinions 195 to 199 inclusive, the depths of the recesses 187 and 190 to 193 inclusive, being slightly deeper than the thickness of each of the pinions 195 to 199 inclusive, so that the top surfaces of the pinions 195 to 199 inclusive, are slightly below flush with the top surface of the horizontally disposed plate portion 180. The pinion 195 is fixedly mounted on the restricted upper end of the vertically disposed shaft 171, by any suitable means such as a dowel pin 201 (Figure 11).

The rearmost knurled roller 161 is fixedly mounted on a vertically disposed shaft 205. The upper end of the roller 161 is adjacent the lower surface of the horizontally disposed plate portion 180 and the shaft 205 is rotatably mounted in, and projects upwardly through, the horizontally disposed plate portion 180 into the recess 193. This shaft 205 has fixedly mounted thereon the pinion 199, by any suitable means such as a dowel pin 206. The lower end of the roller 161 is supported on an outwardly extending portion 207 of an L-shaped bracket 208 which is secured, by any suitable means such as a screw 209, to the front surface of the vertically disposed portion 173, of the bracket 175. The shaft 205 extends downwardly below the lower end of the roller 161 and is rotatably mounted in the outwardly extending portion 207 of the bracket 208.

The front knurled roller 160, which is disposed adjacent the rear knurled roller 161, is fixedly mounted on a vertically disposed shaft 210 and the upper end of this roller 160 is adjacent the lower surface of a block 214, which is slidably mounted in a slot 216 disposed in the plate portion 180 of the bracket 175 and the lower surface of which is also flush with the lower surface of the horizontally disposed plate portion 180. The shaft 210 extends upwardly through the block 214 into a cavity 215 cut in the upper surface of the block 214 to thereby receive a pinion 212 which is secured on the upper end of the shaft 210, by any suitable means such as a dowel pin 213 (Figure 11).

The lower end of the roller 160 is supported on an inwardly projecting portion 220 of an irregularly shaped bracket 221 (Figure 12) and this inwardly projecting portion 220 has rotatably mounted therein the lower end of the shaft 210. The bracket 221 extends upwardly and is integral with an L-shaped horizontally disposed portion 223 which extends forwardly and inwardly in front of the roller 160 and is secured, by any suitable means such as a screw 224, to the lower surface of the block 214. The block 214 has horizontal sliding movement in the horizontally disposed plate portion 180, of the bracket 175, and is slidably mounted on horizontally disposed dowel pins 230 and 231 (Figure 11) which are fixedly mounted in the proximate sides of the slot 216 in

which the block 214 has horizontal sliding movement.

It is manifest that the front roller 160 as well as the bracket 221 will move, on a horizontal plane, whenever the block 214 moves and so that portion of the bracket 223 which extends beneath the horizontally disposed plate portion 180 is cut away, as at 232, so that the bracket 221 will not engage the lower surface of the horizontally disposed plate portion 180. The pinion 212 does not engage the pinion 199 inasmuch as the pinion 212 and associated parts have horizontal movement in the horizontally disposed plate portion 180, the outward movement of which is caused by the thickness of the seamed hose and the inward movement of which is caused by spring means to be later described. Thus, the pinion 212 engages the idler pinion 198 which is rotatably mounted on an upwardly projecting pin 236 and is disposed within the recess 192 of the plate portion 180. The pin 236 is fixedly mounted at its lower end in the plate portion 180.

The pinion 198 in turn engages the pinion 197 which is rotatably mounted on an upwardly projecting pin 237 the lower end of which is secured in the plate portion 180. This pinion 197 then engages the pinion 196 which is rotatably mounted on another upwardly projecting pin 238, the lower end of which is also secured in the horizontally disposed plate portion 180. This pinion 196, of course, engages the driving pinion 195 and thus transmits rotation to the pinion 212 in a counter-clockwise direction as observed in Figures 3, 5 and 6. So that the pinions 195 to 199 and the pinion 212 will not be exposed at the top of the plate member 180, there is secured on the plate 180 a closure plate 181, by any suitable means such as screws 185.

The front face of the block 214 has a groove 240 therein cooperating with a groove 241 in the front face of the horizontally disposed plate portion 180. The grooves 240 and 241 have, slidably mounted therein, an inwardly projecting portion 242 of a bell crank 243. The bell crank 243 is pivotally mounted at its heel on a pin 244 which is fixedly mounted, at each end, in the plate portion 180. The bell crank 243 also has a rearwardly projecting portion 247 integral therewith, the end of which is engaged by a compression spring 250 which extends outwardly from a bore 251 in the left-hand side of the horizontally disposed plate portion 180 as observed in Figures 3 and 8.

It is thus seen that when there is no hose 150 passing between the rollers 160 and 161 the roller 160 will be urged against the roller 161. However, when the selvage edges 147 and 148 of the hose 150 are seamed and passes between the rollers 160 and 161 the roller 160 will move forwardly and, inasmuch as the rollers 160 and 161 are driven so that the surface speed of the rollers 160 and 161 is equivalent to the surface speed of the feeding cups 20 and 72, the hose 150 is urged through the rollers 160 and 161 at a constant rate of speed and thus the tension or tautness of that portion of the hose 150 which is disposed between the feeding cups 20 and 72 and the rollers 160 and 161 will always be consistent.

It is also manifest from this description that the pressure exerted on the hose by the feeding cups 20 and 72 need not be as great as has been in conventional practice, inasmuch as the rollers 160 and 161 assist in drawing the hose 150 through the machine. The rollers 160 and 161 having a very light knurl thereon and also en-

gaging the seamed portion of the stocking rather than that portion which is disposed immediately therebelow, as is the case with the cups 20 and 72, will thus prevent the formation of pull threads and runs from the hose which have heretofore been caused by the serrations or gear teeth 21 and 73 of the feeding cups 20 and 72, respectively, extending too much pressure on the hosiery blank.

The threaded hole on the front surface of the conventional seamer housing 10, in which the screw 183 which secures the bracket 175 to the housing 10 is secured, is ordinarily used for mounting a conventional thread cutter for cutting the thread after the hose 150 has been seamed. However, since this bracket 175 is mounted in the manner stated, it has been necessary to redesign a thread cutter, in the manner shown and, broadly designated at 260.

The thread cutter 260 is L-shaped and has a substantially horizontal arm 261 and a vertical arm 262 and the vertical arm 262 has extending inwardly therefrom an ear 263. The ear 263 is slidably penetrated by screws 264 which are threadably embedded in threaded holes 265 in the vertically disposed portion 177 of the bracket 175 (Figure 11). The substantially horizontal arm of the thread cutter 261 is rounded at its forward end, as at 267, and has a slot 270 cut therein which is adapted to sever the threads as heretofore described.

The guard plate 166, being disposed adjacent the gear wheel 163 and the pinion 170, thus prevents the hose 150 from becoming entangled in the teeth of the gear 163 or the pinion 170 as it passes between the feeding cups 72 and 20 and the knurled rollers 160 and 161.

It is thus seen that in the conventional machine, the feed cups 20 and 72 not only held the selvage edges aligned, but also had to exert enough pressure on the hosiery blank to feed the same through the machine. By the addition of the additional feeding mechanism which exerts pressure on the seamed edge and not on the knitted fabric adjacent the seam, no damage is imparted to the fabric adjacent the seam. Thus the cups 20 and 72 are employed to hold the fabric with the two selvage edges projecting above the cups for the seaming operation, and the auxiliary feed serves to pull the hose through the machine.

In the drawings and specification there has been set forth a preferred embodiment of the invention and although specific terms are employed, they are used in a generic and descriptive sense only, and not for purposes of limitation, the scope of the invention being defined in the claims.

I claim:

1. In a machine for seaming the two edges of a hosiery blank together and having a pair of rotary feeding means between which the edges of the blank are fed so that the selvedge edges project slightly outside of the path of travel of the feeding means and having looping mechanisms for forming a row of stitches to secure the selvedge edges of the hosiery blank together, a pair of auxiliary feed rollers disposed a substantial distance away from the point of seaming and disposed for engagement with the seamed selvedge edge of the stocking to pull the same through the machine, said auxiliary feed rollers being driven by the machine at approximately the same surface speed as the first-named means and whereby the seamed stocking is held tautly between the point of seaming and where it passes 70 the auxiliary feed rollers.

2. In a structure according to claim 1, resilient means for pressing one of the auxiliary feed rollers toward its associated feed roller.

3. In a hosiery seaming machine for seaming together the selvedge edges of a hosiery blank and having a pair of rollers between which the edges of the blank are passed so that the edges of the blank project substantially above the upper surface of the rollers and having sewing mechanism for forming a line of stitches through and over the selvedge edges of the blank and having resilient means pressing the two rollers together, additional feeding means disposed remotely from the first-named feeding means and having a pair of driven rollers resiliently mounted relative to each other and disposed to engage the seamed edge of the stocking and thereby assist the conventional feeding means in propelling the stocking through the machine.

4. In a hosiery seaming machine having means for feeding the selvedge edges of a hosiery blank through the machine and forming a line of stitches through and over the selvedge edges, additional means for moving the stocking through the machine comprising a pair of rollers disposed remotely from the first-named feeding means and between which the selvedge edge of the stocking is adapted to be passed after the edges thereof have been seamed together, means for driving both of the rollers in the auxiliary feeding means at substantially the same surface speed as the first-named feeding means to thereby exert an additional pull on the stocking to assist the conventional feeding means in feeding the stocking through the machine, one of the first-named feeding means being resiliently mounted to press the selvedge edge of the stocking toward the other of the first feeding means, and whereby the pressure between the proximate surfaces of the rollers of the first feeding means may be substantially lessened to prevent damage to the stocking blank by the first-named feeding means.

5. In a sewing machine, stitch-forming mechanism including a horizontally disposed endwise reciprocating needle, opposed feed-cups rotatable about substantially vertical axes and disposed below the path of reciprocation of said needle for supporting and advancing work past said stitch-forming mechanism, and pull-feed mechanism including opposed work-engaging members both disposed at the work-discharge side of said feed-cups and each having a work-gripping surface extending above the upper surfaces of said feed-cups so as to engage the opposite sides of the work at the level of seam formation, said pull-feed mechanism having at least one of its work-engaging members driven.

6. In a sewing machine, stitch-forming mechanism including a horizontally disposed endwise reciprocating needle, opposed feed-cups rotatable about substantially vertical axes and disposed below the path of reciprocation of said needle for supporting and advancing work past said stitch-forming mechanism, and pull-feed mechanism including opposed work-engaging members both disposed at the work-discharge side of said feed-cups and each having a work-gripping surface extending above the upper surface of said feed-cups so as to engage the opposite sides of the work at the level of seam formation, said pull-feed work-engaging members being positioned to effect a straight line travel of the work between said feed-cups and said work-engaging members.

7. In a sewing machine, stitch-forming mechanism including a horizontally disposed endwise reciprocating needle, opposed feed-cups disposed below the path of reciprocation of said needle for advancing work past said stitch-forming mechanism, and pull-feed mechanism including opposed work-engaging members both disposed at the work-discharge side of said feed-cups and both having work-gripping surfaces extending through the horizontal plane containing the path of reciprocation of said needle.

8. A sewing machine having stitch-forming devices including a reciprocating needle, opposed feed-cups having cooperating work-engaging faces for supporting and feeding work past said stitch-forming devices, a chaining finger disposed above said feed-cups and having a blade about which the stitches are formed and set, and opposed feed-members disposed at the discharge side of the feed-cups at a point removed from the point of seaming and having cooperating work-engaging faces extending above and below the level of the longitudinal axis of said chaining-finger blade for exerting a pulling action on the seam at the level of seam formation.

9. A sewing machine having stitch-forming devices including a reciprocating needle, opposed feed-cups having cooperating work-engaging faces for supporting and feeding work past said stitch-forming devices, a chaining finger disposed above said feed-cups and having a blade about which the stitches are formed and set, and driven opposed feed-rollers disposed at the discharge side of the feed-cups and having cooperating work-engaging faces disposed on opposite sides of the work and extending above and below the level of the chaining-finger.

10. In a sewing machine, stitch-forming mechanism including a horizontally disposed endwise reciprocating needle, opposed feed-cups rotatable about substantially vertical axes and disposed below the path of reciprocation of said needle for supporting and feeding the work past said stitch-forming mechanism, and pull-feed mechanism including opposed work-engaging members both disposed at the work-discharge side of said feed-cups for engagement with opposite sides of the work at the level of seam formation, a single bracket supporting both of said work-engaging members, and driving connections for actuating at least one of said work-engaging members.

11. In a sewing machine, stitch-forming mechanism including a horizontally disposed endwise reciprocating needle, opposed feed-cups rotatable about substantially vertical axes and disposed below the path of reciprocation of said needle for supporting and feeding the work past said stitch-forming mechanism, and pull-feed mechanism including opposed driven work-engaging members both disposed at the work-discharge side of said feed-cups for engagement with opposite sides of the work at the level of seam formation, actuating mechanism for imparting movement to said work-engaging members including a pinion, and a driving gear mounted coaxially with one of said feed-cups and meshing with said pinion.

12. In a sewing machine, stitch-forming mechanism including a horizontally disposed endwise reciprocating needle, opposed inner and outer feed-cups disposed below the path of reciprocation of said needle for supporting and feeding the work past said stitch-forming mechanism, shafts supporting each of said feed-cups, means for ac-

13

tuating said shafts, and pull-feed mechanism including opposed feed-rollers disposed at the discharge side of the feed-cups, and means for rotating at least one of said feed-rollers, said means including a shaft, a pinion fast on said shaft, and a driving gear meshing with said pinion and carried by the shaft supporting said inner feed-cup.

13. In a sewing machine, stitch-forming mechanism including a horizontally disposed endwise reciprocating needle, opposed inner and outer feed-cups disposed below the path of reciprocation of said needle for supporting and feeding the work past said stitch-forming mechanism, shafts supporting each of said feed-cups, means for rotating said shafts, and pull-feed mechanism including opposed feed-rollers disposed at the discharge side of the feed-cups, and means for rotating at least one of said feed-rollers, said last named means including driving connections between one of said feed-cup supporting shafts and at least one of said feed-rollers.

14. A pull-feed unit adapted for attachment to a cup-feed sewing machine having a horizontally disposed endwise reciprocating needle, comprising a pair of opposed feed-rollers, a feed-roller supporting bracket adapted to be secured to said sewing machine in position to support the feed-rollers at the work-discharge side of the feed-cups, an actuating shaft journaled in said supporting bracket and adapted to be operatively connected to a moving element on said sewing machine, and driving connections between said actuating shaft and said feed-rollers.

15. A pull-feed unit adapted for attachment to a sewing machine having a frame, a horizontally disposed endwise reciprocating needle, and opposed feed-cups disposed below the path of reciprocation of said needle, comprising a pair of opposed feed-rollers, a feed-roller supporting bracket adapted to be secured to the machine frame in position to support the feed-rollers at the work-discharge side of the feed-cups, an actuating shaft journaled in said supporting bracket and adapted to be operatively connected to a moving element on said sewing machine, means supporting one of said feed-rollers for yielding movement relative to the other of said feed-rollers, and gearing connecting each of said feed-rollers to said actuating shaft.

16. In a sewing machine, stitch-forming mechanism including a horizontally disposed endwise reciprocating needle, opposed inner and outer work-advancing feed-cups rotatable about substantially vertical axes and disposed below the path of needle-reciprocation, means including a vertical axis feed-cup carrying shaft for rotating said feed-cups, and pull-feed mechanism comprising opposed work-engaging members including a driven pull-feed roller disposed at the work-discharge side of said feed-cups, said members having work-engaging surfaces intersecting the horizontal plane containing the path of needle-reciprocation, and actuating mechanism including said feed-cup carrying shaft for rotating said pull-feed roller.

17. In a sewing machine, stitch-forming mechanism including a horizontally disposed endwise reciprocating needle, work-advancing mechanism including opposed inner and outer feed-cups rotatable about substantially vertical axes and disposed below the path of needle-reciprocation, and pull-feed mechanism comprising op-

14

posed work-engaging members including a driven pull-feed roller disposed at the work-discharge side of said feed-cups, said work-engaging surfaces intersecting the horizontal plane containing the path of needle-reciprocation, and operative connections with said work-advancing mechanism for rotating said driven roller.

18. In a sewing machine, stitch-forming mechanism including a horizontally disposed endwise reciprocating needle, opposed inner and outer feed-cups rotatable about substantially vertical axes and disposed below the path of reciprocation of said needle for advancing work past said stitch-forming mechanism, and pull-feed mechanism comprising opposed work-engaging members including a driven inner feed-roller disposed at the work-discharge side of said feed-cups and both having work-engaging surfaces extending above and below the horizontal plane containing the path of needle-reciprocation, and means for driving said inner feed-roller including intermeshing gears disposed entirely at the inner feed-cup side of the work.

19. In a sewing machine, a machine-frame, stitch-forming mechanism including a horizontally disposed endwise reciprocating needle, opposed inner and outer feed-cups rotatable about substantially vertical axes and disposed below the path of needle-reciprocation for advancing work past said stitch-forming mechanism, and pull-feed mechanism including opposed inner and outer work-engaging members both disposed at the work-discharge side of said feed-cups and both having work-engaging surfaces extending through the horizontal plane containing the path of needle-reciprocation, said inner work-engaging member comprising a driven roller, a bracket attached to said machine-frame for supporting said inner roller, and driving means including gearing supported by said bracket for rotating said inner roller in timed relation with said feed-cups.

20. In a sewing machine, a machine-frame, stitch-forming mechanism including a horizontally disposed endwise reciprocating needle, opposed inner and outer feed-cups mounted on vertically disposed shafts and disposed below the path of needle-reciprocation for advancing work past said stitch-forming mechanism, the combination of a puller mechanism comprising a plurality of work-engaging members arranged to engage the opposite faces of the work at the discharge side of said feed-cups, one of said members comprising a driven roller, a bracket attached to said machine-frame and supporting said driving roller for rotation about a vertical axis, gearing supported by said bracket and driven in response to rotation of one of said shafts for driving said driven roller, and another of said members being resiliently urged into engagement with said roller.
